JAMES M. CONNEL AND JOHN CONNEL, JR., OF NEWARK, OHIO

Letters Patent No. 65,795, dated June 18, 1867.

IMPROVEMENT IN SLATE-FRAMES

The Schedule referred to in these Letters Patent and making part of the same.

TO ALL WHOM IT MAY CONCERN:

Be it known that we, JAMES M. CONNEL and JOHN CONNEL, Jr., of Newark, in the county of Licking, and State of Ohio, have made a new and useful Improvement in School Slates; and we do hereby declare the following to be a full, clear, and exact description thereof, sufficient to enable one skilled in the art to which it appertains to construct and use the same, reference being had to the accompanying drawing, making part of this, our specification, and in which similar letters indicate like parts.

The frame of the slate is held together by ornamental corner casings made of India rubber, leather, or other analogous material, the resiliency of which affords a protection to the slate when falling on its side, edge, ends, or corners, and also obviates the noise of the slate upon the desks in school.

In the drawing, A is the slate, inserted by its edge, as usual, in the groove or rabbet of the frame B, the pieces of which are jointed together in the usual manner by tenon and mortise, or by a mitre joint. C are ornamental corner casings or covers, which lap upon each side of the slate and embrace its edges for some distance, as represented. They can be made of any pattern and style of ornamentation that may be desired, and to increase their resiliency their inner surface may be cellular, so that a fall or careless placing of the slate on the desk or table may be attended with as little noise as possible. It will be observed at the corners, where the facing of the casing is removed to display the construction, that the angle of the corners of the frame is rounded off and the elastic material is thickest at this point b. This is for the purpose of protection at the point most exposed to wear and most likely to strike the floor when falling. Notches d are made in the frame to receive the entering flanges m of the cap or corner cover which is placed in position by expanding it sufficiently to slip over the corner of the frame B so as to allow the flanges m to enter the notches d, and the triangular ornamental portion to be closed to the flat sides of the frame. The direction of the notches d, as shown in the drawings, causes the flanges to become hooked into the frame so as not to be too readily withdrawn. This corner casing may be readily applied to any wooden-frame slate.

We do not claim fastening the corners of the slate by a wire or other metallic strap which embraces notches in the edges of the slate.

Having described our invention, what we claim as new, and desire to secure by Letters Patent, is—

A corner casing of elastic or resilient material, constructed substantially as described, to hook into the notches in the edges of the slate.

To the above specification of our improvement in slate we have set our hands this 20th day of February, 1867.

J. M. CONNEL,
JOHN CONNEL, JR.
